FROZEN CONFECTION

James S. Merritt, Shawnee Mission, Kans., assignor to The James S. Merritt Company, Kansas City, Mo., a corporation of Missouri

Filed Nov. 19, 1965, Ser. No. 88,153

Term of patent 14 years

(Cl. D82—2)

Fig. 1.

Fig. 2.

Fig. 3.

Fig. 4.

FIG. 1 is a side elevational view of a frozen confection embodying my new design;

FIG. 2 is another side elevational view thereof as it appears rotated 90° from the view in FIG. 1;

FIG. 3 is a top plan view of the frozen confection of FIG. 1; and

FIG. 4 is a bottom plan view of the frozen confection in the orientation of the view of FIG. 2.

The dominant features of the design reside in the portions shown in solid lines.

I claim:

The ornamental design for a frozen confection, as shown and described.
